(57) **CLAIM**

The ornamental design for a disc cartridge, as shown and described.

DESCRIPTION

FIG. 1 is a perspective view of the front, bottom and right side of a disc cartridge showing our new design;

FIG. 2 is a front view thereof;

FIG. 3 is a top plan view thereof;

FIG. 4 is a bottom view thereof;

FIG. 5 is a left side view thereof;

FIG. 6 is a right side view thereof;

FIG. 7 is a rear view thereof; and,

FIG. 8 is a perspective view thereof, the shutter is shown in open condition, the rear view is similar to FIG. 7 except that the middle portion would be an opening.

1 Claim, 3 Drawing Sheets
